(57) **CLAIM**

The ornamental design for a pot filler, as shown and described.

DESCRIPTION

FIG. 1 is a perspective view of a pot filler shown in a condition of use in a surface mount configuration showing our new design;

FIG. 2 is a perspective view of a pot filler shown in a condition of use in a wall mount configuration;

FIG. 3 is a side view of the pot filler showing our new design;

FIG. 4 is a rear view of the pot filler showing our new design;

FIG. 5 is a front view of the pot filler showing our new design; and,

FIG. 6 is a top view of the pot filler showing our new design.

The broken lines are included for the purpose of illustrating portions of the pot filler that forms no part of the claimed design.
